UNITED STATES PATENT OFFICE.

GEORGE F. THIELMAN, OF ST. CLOUD, MINNESOTA.

STAIR-RULE.

1,349,348.

Specification of Letters Patent. Patented Aug. 10, 1920.

Application filed April 8, 1919. Serial No. 288,477.

To all whom it may concern:

Be it known that I, GEORGE F. THIELMAN, a citizen of the United States, resident of St. Cloud, county of Stearns, State of Minnesota, have invented certain new and useful Improvements in Stair-Rules, of which the following is a specification.

In building a stairway, a carpenter, owing to the variation in the distance between the side rails or stringers of the stairs, is often obliged if the lumber for the steps is cut the same length, to insert shims or wedges between the stringers and the ends of the treads or risers and this make-shift renders the steps less secure and involves a waste of considerable time in building a stairway.

The object of my invention is to provide a rule by means of which the carpenter can easily ascertain the exact distance between the opposite faces of any portion of the stringers or rails and then placing the rule on a piece of lumber can cut it to exactly fit the space.

A further object is to provide a rule which can be easily and quickly folded into compact form for packing away or for transportation.

The invention consists generally in various constructions and combinations, all as hereinafter described and particularly pointed out in the claims.

In the accompanying drawings forming part of this specification,

Figure 1 is a perspective view of a rule embodying my invention, placed on a piece of lumber ready to cut a tread therefrom,

Fig. 2 is a view, showing the rule inserted between the stringers or rails of the stairway to ascertain the exact distance between them and any variation in the surface of the pieces of lumber forming the stairway.

Fig. 3 is a sectional view showing the manner of using the rule,

Fig. 4 is a sectional view on the line 4—4 of Fig. 1,

Fig. 5 is a sectional view on the line 5—5 of Fig. 1,

Fig. 6 is a sectional view on the line 6—6 of Fig. 1,

Fig. 7 is a perspective view of a modified construction of the rule,

Fig. 8 is a section on the line 8—8 of Fig. 1.

In the drawing, 2 represents one section of the rule, and 3 the other section. These sections are placed one upon the other and

a metallic loop 4 is secured to one end of the section 2 and extends down under the section 3 and forms a guide wherein said section 3 is slidable. The section 3 is provided with a suitable loop 5 which extends over the section 2 and forms a guide therefor, and a clamping screw 6 is mounted in the loop 5 for engaging the section 2 and locking the sections against relative movement when the desired adjustment is obtained. By loosening this clamping screw the sections may be moved longitudinally one upon the other to increase or decrease the length of the rule.

The ends of the sections 2 and 3 are provided with plates 7, each being of elbow shape with one leg secured lengthwise of and to the respective section and its lateral leg bent from the plane of the first leg to form a depending lug 8 which functions as a stop when the rule is placed on the piece of lumber to be cut for guiding and seating the rule on the lumber. Screws 8^a pass through the ends of the plates 7 and

through the bars 2 and 3 and are provided with thumb nuts 9 and comparatively thin arms 10 having longitudinal slots 11 therein to receive the shanks of the screws 8^a and be locked thereby on the plate 7. When the thumb nuts 9 are loosened, these arms 10 may be swung on a vertical axis to any desired angle with respect to the bars 2 and 3, the outer edges of the arms being slightly beyond the ends of the bars or sections 2 and 3 for contact with the inner faces of the stringers, and when these bars have been seated on said faces, the thumb nuts 9 are tightened, clamping the bars securely, and their outer edges will be at the same angle with respect to the bars of the rule as the faces of the stringers. Some stringers will be clear, straight lumber and the arms may assume a right angle position

with respect to the rule bars and this may be the case for some distance between the stringers, but there may be a point or several points where the stringers will be warped or twisted in such a way that the lumber for the steps can be cut square across but the ends must be oblique slightly to fit the surfaces of the stringers. When the carpenter places the rule on such a part of the stair stringers, the arms will indicate the irregularity and when the rule is placed on the lumber to be cut the arms will

show the exact variation from the right

angle and the lumber may be marked and cut accordingly. The slotted ends of the arms allow for convenient adjustment lengthwise and the arms are made sufficiently thin so that when the tool is not in use the arms may be swung around in line with the bars and the ends inserted respectively through the guides 4 and 5.

In Fig. 7 I have shown a modification which consists in providing an angle plate 12 at the end of the bar inserted between an arm 13 and a bar 3 through which the screws pass for securing the angle plate and the arm to the bar of the rule. In this case I have shown a wing nut 14 for locking the plate and arm together. This arm is also inserted between the loop 15 and the face of the bar when the tool is not in use, the gap 16 provided between the loop 4 and the bar 3 being plainly indicated in Fig. 5.

With this device a carpenter can easily and quickly determine the exact distance between the side rails or stringers of a stairway and cut the threads to accurately fit the space and eliminate entirely the extra time and labor usually required in building a stairway when all the treads are cut the same length.

I claim as my invention:

30 1. A stair rule comprising a pair of extensibly connected bars, arms mounted on the outer ends of the bars for adjustment against the inner faces of the stair stringers when positioned therebetween, stop members secured to the outer ends of the bars, and means including a single member for securing each stop member and the adjacent arm fixed to the respective bars.

40 2. A stair rule comprising a pair of bars mounted to slide one upon the other, an arm slidably and pivotally mounted on the outer end of each bar, and a guide loop on the inner end of each bar guidingly receiving the companion bar and designed to receive the adjacent arm when the latter is folded into registry with the respective bar and then moved lengthwise thereof for holding the arms in their folded inoperative position.

3. A stair rule comprising a pair of bars 50 mounted to slide one upon the other, an arm slidably and pivotally mounted on the outer end of each bar, a guide loop on the inner end of each bar guidingly receiving the companion bar and designed to receive the adjacent arm when the latter is folded into registry with the respective bar and then moved lengthwise thereof for holding the arms in their folded inoperative position, means for securing the arms at their predetermined angular adjustments, and a single means carried by one of said loops for adjustably securing the bars in their extended operative position and the arms together with the bars in their folded and 65 telescoped inoperative position.

4. A stair rule comprising a pair of bars mounted to slide one upon the other, an arm slidably and pivotally mounted on the outer end of each bar, a guide loop on the inner 70 end of each bar guidingly receiving the companion bar and designed to receive the adjacent arm when the latter is folded into registry with the respective bar and then moved lengthwise thereof for holding the 75 arms in their folded inoperative position, and stop means carried by the bars for abutment against the work and adapted to limit the folding action of the arms when the latter are disposed for insertion in the 80 guide loops.

5. A stair rule comprising a bar-like body, an arm movably connected to each end thereof, an elbow member secured to each end of the body adjacent the respective arm with one leg extended lengthwise of the body across said arm and the other leg extended laterally and deflected to form a stop spaced inwardly from the arm, and a single clamping device for securing each 90 arm and its lapping leg of the elbow member to the body.

In witness whereof, I have hereunto set my hand this 2nd day of April, 1919.

GEORGE F. THIELMAN.
